A. M. ULLMAN.
ATTACHMENT FOR SAFES.
APPLICATION FILED MAY 18, 1921.

1,405,641.

Patented Feb. 7, 1922.

UNITED STATES PATENT OFFICE.

AUBREY M. ULLMAN, OF SPRINGFIELD, MISSOURI, ASSIGNOR OF ONE-HALF TO W. A. WALLENDER, OF SPRINGFIELD, MISSOURI.

ATTACHMENT FOR SAFES.

1,405,641.

Specification of Letters Patent. Patented Feb. 7, 1922.

Application filed May 18, 1921. Serial No. 470,688.

To all whom it may concern:

Be it known that I, AUBREY M. ULLMAN, a citizen of the United States, and a resident of Springfield, in Green County and State 5 of Missouri, have invented certain new and useful Improvements in Attachments for Safes, of which the following is a specification.

My invention relates to an adjustment for 10 safes, vaults and the like, and more particularly to an arrangement wherein a container of noxious gas or liquid may be positioned so that upon an unauthorized opening of the safe the same may be spilled or freed, making 15 the vicinity of the safe untenable.

Various arrangements have heretofore 20 been used wherein noxious gases have been employed to burglar proof safes and vaults, but generally speaking, in prior arrangements, there was always the danger of causing 25 the gas to function upon an authorized opening of the safe, thereby, making the use of the same dangerous. It is, therefore, the object of my invention to provide an arrangement of this type wherein the support 30 for the container which carries the noxious fluid or gas may be quickly and conveniently removed when a continued use of the safe is desired.

In carrying out my invention, I provide a 35 supporting member or frame adapted to receive a glass receptacle in which is contained the noxious fluid or gas. A pin and slot connection is provided between this supporting member and the floor of the safe so arranged that the supporting member and with it, the glass receptacle may be quickly removed from its position at the door of the safe. I further provide a fracturing device 40 for breaking the glass receptacle, which fracturing device is adapted to be connected to the locking bolt of the safe door by a clutch controlled by the sliding movement of the safe door bolt.

Therefore, when the safe door is opened 45 by one having the proper authority, the fracturing device will be disconnected whereby danger of accidentally freeing the noxious gas is eliminated. On the other hand, when 50 the safe door is forced open, the fracturing device functions, breaking the glass receptacle to free the gas contained therein, whereby it will function to make the vicinity of the safe untenable.

The particular features of my invention

will be made more apparent in the accompanying specification and drawings in which:

Fig. 1 is a sectional view of a front corner 60 of a safe with my improved device in position,

Fig. 2 is a vertical section of the structure shown in Fig. 1,

Fig. 3 is a fragmentary perspective view of the clutch mechanism,

Fig. 4 is a bottom plan view of the supporting member and,

Fig. 5 is a diagrammatic plan view showing the manner of attaching the supporting member to the floor of the safe or vault.

In the drawings S represents a safe or 70 vault provided with a door D and a bottom B. The door D is provided with a door bolt C of usual construction. The invention consists primarily of a metal holder or supporting member 10, open at its top end. 75 This supporting member is carried by a base 11 preferably of wood and is secured thereto by screws 12 passing through lugs 13 formed on the supporting member 10. Inasmuch as it is necessary that the top of the holder 80 or supporting member be in substantial alignment with the bolt C of the safe door, the thickness of the base 11 may be varied to properly position the holder 10.

Secured to the under side of the base 11 85 is a metal plate 14 held in place preferably by screws 15. The base 11 is provided with a longitudinally extending groove 16 stopping short of one end of the base as indicated at 17. A transversely disposed groove 18 extends from the longitudinal groove 16 to one 90 side of the base 11. The plate 14 is provided with a corresponding longitudinally disposed slot 19 and a transversely disposed slot 20. The pair of grooves just described are 95 adapted to cooperate with a pair of pins 21 and 22 respectively projecting from the bottom B of the safe, for removably securing the holder or supporting member 10 in position within the safe.

At oppositely disposed points on the top edge of the supporting member there is provided a slot 23 and a pair of lugs 24. Between the pair of lugs 24 there is pivotally mounted a fracturing bar 25. This bar has 105 a depending end 26 adapted to rest within the slot 23. Connection between the lugs 24 and the fracturing bar 25 is made by a pin 27 made preferably of soft metal.

The end of the fracturing bar 25 adjacent

the door is provided with a head 28 forming one part of a clutch arrangement. A movable portion of the clutch comprises a pair of members 29 having laterally disposed projections 30. The members 29 are clamped upon the door bolt C by clamping bolts 31.

When the pair of members 29 are in position upon the door bolt C the projections 10 30 are in position to engage the head 28 on the fracturing bar 25, whereby a movement of the door will be imparted to the fracturing bar, to cause the device to function.

15 Into the holder 10 is adapted to be inserted a removable glass container 32. The glass container is for holding a noxious liquid or gas whereby, upon fracture of the receptacle, the liquid or gas will be spilled or permitted to escape thereby making the 20 vicinity of the safe untenable.

In order to mount the holder in position at the door of the safe, it is placed in position so that the pin 21 will enter the groove 25 formed by the groove 16 of the base and the slot 19 of the plate. The holder is then moved in the direction of the arrow (Fig. 5), in a longitudinal direction until the pin 21 is disposed in the closed end 17 of the slot. The holder is then swung with the pin 21 as a pivot, thereby bringing the groove formed by the groove 18 and the slot 20 into position to engage the pin 22. With the pins in position in the grooves 30 the holder will be properly disposed at the 35 door of the safe.

The glass receptacle 32 containing the noxious liquid or gas is then inserted in the holder 10. The fracturing bar 25 is then 40 mounted between the lugs 24 and pivoted there-between by the pin 27. The depending end 26 is thus disposed in the slot 23 and contacts the upper end of the glass receptacle 32. The head 28 of the fracturing bar 45 is engaged by the projections 30 of the pair of members 29.

When a person with authority opens the safe, the door bolt C will be moved longitudinally carrying with it the pair of members 29 to a position such as shown in dotted lines in Fig. 2. In this position the projections 30 are out of engagement with the head 28 of the fracturing bar, whereby the possibility of accidentally moving the fracturing bar to break the receptacle 32 is eliminated. Furthermore, because of the pivotal support of the fracturing bar 25 when the safe has been opened, the inner end 55 of the fracturing bar may be raised and the glass container removed.

When, however, the safe door is blown open or forced in some other manner without having first properly moved the door bolt C, this movement of the door will cause 60 a longitudinal pull on the fracturing bar

25, by reason of the engagement of the clutching members 28-30. This movement of the fracturing bar 25 will shear off the soft metal pin 27 and cause the depending end 26 to fracture the glass receptacle 32, thereby freeing its contents.

Thus, it will be seen that a structure is provided which, upon legitimate use of the safe will be harmless and the danger of accidental fracture of the glass receptacle 75 is minimized. On the other hand when the door of the safe or vault is forced or illegitimately opened, the operation of the device is positively assured.

Furthermore, it should be noted that the 80 base of the supporting member is so constructed that the entire device may be quickly and easily removed without the manipulation of screws, bolts or the like.

While the structure described and illustrated herein has proved to be an efficient one, I do not wish to be unnecessarily limited and reserve the right to make such modifications as come within the purview 85 of the accompanying claims.

Having thus described my invention, what I claim is:

1. The combination with a safe provided with a door of a device of the class described, said device consisting of a holder, a receptacle for noxious fluids adapted to be supported by said holder, slidably engageable means whereby said holder may be removably secured to the base of the safe, a fracturing bar for breaking said glass receptacle 95 and means connecting said fracturing bar to said door, whereby said connection may be disconnected upon an authorized opening of the door of the safe.

2. A device of the class described in combination with a safe, said device comprising a holder, a glass container adapted to be mounted within said holder and containing a noxious fluid, a fracturing bar supported upon said holder, a clutching connection between the door of the safe and said fracturing bar whereby upon an authorized opening of the door the clutch will be disconnected and means for removably securing said holder to the floor of the safe, said means embodying a pair of pins projecting from the safe floor and a pair of cooperating grooves provided on the bottom of said holder.

3. An arrangement of the class described for use in combination with a safe comprising a metal holder, said holder being adapted to receive a glass containing a noxious fluid, a wooden base for said holder, a metal plate secured to said wooden base, said base and 120 plate being formed with cooperating slots, a pair of pins projecting from the bottom of said safe and adapted to enter said slots for removably securing said holder in place within the safe, a pair of lugs projecting 125

from the upper edge of said holder, a fracturing bar pivotally mounted between said lugs, one end of said fracturing bar engaging said glass container, a pair of members 5 clamped to the door bolt of the safe door, said members having laterally disposed projections, a head formed on one end of said

fracturing bar and adapted to be engaged by said laterally extending projections, whereby when an unauthorized opening of 10 the safe door occurs, the fracturing bar will be moved to break said receptacle and free its contents.

AUBREY M. ULLMAN.
